UNITED STATES PATENT OFFICE.

ROBERT J. HEWETT, OF WESTFIELD, NEW JERSEY.

DIRECTIONALLY-CONTROLLED SIGNAL SYSTEM.

1,380,145.

Specification of Letters Patent.

Patented May 31, 1921.

Application filed January 16, 1918. Serial No. 212,021.

To all whom it may concern:

Be it known that I, ROBERT J. HEWETT, a citizen of the United States, residing at Westfield, in the county of Union and State 5 of New Jersey, have invented certain new and useful Improvements in Directionally-Controlled Signal Systems, of which the following is a full, clear, and exact description.

This invention relates to absolute permissive or directionally-controlled automatic block-signal systems, such systems being particularly adapted for use upon single stretches of single track over which traffic proceeds in both directions.

15 One of the objects of the invention is to provide a system of this character in which the absolute and permissive control of the signals is obtained by means of a polar selective relay which is preferably arranged so

20 that in its normal condition it provides for the permissive control and in its reverse condition it provides for the absolute or through control.

It is also an object of the invention to 25 provide a system in which the polar selective relay may be positioned adjacent a signal which is located one or more blocks in advance of the point at which the train enters the stretch of track.

30 Further objects of the invention will be apparent from the detailed description hereinafter to follow when taken in conjunction with the accompanying drawings and the novel features of the invention will be particularly pointed out in the appended claims.

In the drawings:

Figures 1 and 2, taken together, show diagrammatically one embodiment of the invention.

40 The embodiment of the invention disclosed is suitable for the requirements of a short block between two passing sidings W and X, there being a pair of intermediate signals 11 and 12 providing for the permissive control of the traffic. The signal 11, as well as the signals 9 and 13 at the ends of the block control the traffic in one direction, as for example, west bound traffic. In the same manner, the intermediate signal 12 and 45 the end signals 10 and 14 control the traffic in the opposite direction, as for example, the east bound traffic.

The line control circuits for these signals are of the usual polarized type, the signals 55 being three-position indication signals, the indications being zero, 45° and 90°, as is the

usual construction, the 90° position indicating "clear" or "proceed," the 45° position indicating "caution" or "proceed with caution" and the zero position indicating "stop."

Referring first to the line control circuits for the intermediate signal 11, which is a west bound signal, the circuit for this signal is as follows: from line control relay L¹¹ at 65 signal 11, line wire 60, contact 61 of track relay R¹², wire 62, contact 63 of track relay R¹¹, wire 164, contact 165 of track relay R¹⁰, wire 166, positive pole changer P actuated by signal 9, wires 167 and 168, battery B⁹, 70 wire 169, negative pole changer N actuated by signal 9 and the common wire C back to the common terminal of the line relay L¹¹ at the signal 11.

The control circuit for the west bound 75 signal 13 at passing siding X is as follows: from line control relay L¹³, wire 260, contact 261 of track relay R¹⁵, wire 262, contact 63 of track relay R¹⁴, wire 64, polar contact 65 of west bound selector relay S¹¹, wire 66, 80 positive pole changer P which is actuated by signal 11, wires 67 and 68, battery B¹¹, wires 69 and 70, negative pole changer N actuated by signal 11 and the common wire C back to line relay L¹³. The line control 85 circuit for the west bound signal 9 is only partially shown, the circuit starting from line relay L⁹ passing by wire 160 to contact 161 of track relay R⁹ and by wire 162 to the block to the west of the signal 9. The line 90 control relays L⁹, L¹¹ and L¹³ of the west bound signals are of a type known as neutral polar relays and govern the motor circuits of the signal as will be explained in conjunction with the west bound relay L¹¹. 95

This relay is provided with a neutral armature which, when energized, will hold its front contacts 52, 32 and 40 closed and when deenergized will open these front contacts and will close the back contacts 42 and 43. 100 The relay also controls a polarized armature and contact 56 which is in open or closed position depending upon the direction of current which is passed through the magnet L¹¹. The direction of current through the line relay L¹¹ is controlled by the pole changer N and P actuated by the west bound signal 9 at the passing siding W for, as has been already described, the circuit for the line control relay L¹¹ passes through this 105 pole changer and the battery B⁹. This pole changer at the signal 9 and at the other sig-

nals in the system is so constructed that when the signal 9 is in its either 45° or its 90° position, the pole changer will be in its normal position as is shown in the diagrammatic view and therefore current of normal direction will pass from the battery 9 to the line relay L^{11} to energize this relay in its normal magnetic condition and therefore hold its polar contact 56 closed.

- 10 When the line relay L^{11} is energized in its normal condition, the motor circuit which holds the signal 11 in its 90° position will be closed, the motor circuit being as follows: from the positive terminal of the battery B^{11} , wire 68, wire 31, wire 51, contact 52, wire 55, polar contact 56, wire 57 to the 90° motor movement (not shown), wire 54, wires 70 and 69 to the negative terminal of the battery B^{11} . The motor circuit controlling the 45° position of the motor is also closed, this circuit being as follows: from the positive terminal of the battery B^{11} , wire 68, wire 31, wire 51, contact 52, wire 53 to the 45° motor movement of the signal (not shown), wire 54, wires 70 and 69 to the negative side of the battery B^{11} . It will, therefore be seen that the motor circuit for the 45° position is closed through the neutral contact 52 of the line relay L^{11} , but the 90° position is controlled not only by the neutral contact 52, but also by the polar contact 56 requiring that the line relay L^{11} be energized by current of the normal direction to close the polar circuit to the 90° position, as is shown in the drawing.

40 The line control relay L^9 at the signal 9, is also provided with motor circuits, the 45° position of which is controlled by the neutral contact 152 and the 90° position of which is controlled by the neutral contact 152 and the polar contact 156. In the same manner, the motor circuits for the signal 13 are controlled by the neutral contact 252 and the polar contact 256.

- 45 As before stated, the line control relay L^{13} is controlled by the polar contact 65 of the polar selector relay S^{11} . This polar selector relay is in turn controlled by a local pole changing circuit at signal 11 which is controlled by the line relay L^{11} , the circuit being as follows: from positive terminal of the battery B^{11} , wire 68, wire 31, front contact 32 of line relay L^{11} , wire 33, wire 34, polarized relay S^{11} , wire 35, contact 36 of track relay R^{14} , wire 37, circuit controller 38 of the west bound signal 11, wire 39, front contact 40 of line relay L^{11} and wires 41 and 69 back to the negative terminal of the battery B^{11} . When the line relay L^{11} is energized and the front contacts 32 and 40 of line relay L^{11} closed, the polar selector relay S^{11} will be energized in its normal condition to close the polar contact 65. On the other hand, when the line relay 65 L^{11} is deenergized, the front contacts 32

and 40 will be open and the back contacts 42 and 43 closed, which will reverse the current flowing from the battery B^{11} through the polarized relay S^{11} , the circuit now being as follows: from the positive terminals 70 of the battery B^{11} , wire 68, wire 31, back contact 42, wire 39, circuit controller 38, wire 37, contact 36 of track relay R^{14} , wire 35, polarized selector relay S^{11} , wire 34, back contact 43, wires 41 and 69 to the negative 75 terminal of the battery B^{11} . This energization of the polarized relay S^{11} by a current of reverse direction, will cause the reverse magnetic condition of the magnet S^{11} to open its polar contact 65. The result of 80 opening the contact 65 is to open the circuit to the line control relay L^{13} of the west bound signal 13 and since the neutral contact 252 is thereby opened the motor circuits to both the 45° and 90° position of 85 the signal will be broken and this signal will drop to indicate "danger" or "stop."

90 Referring now to the circuits which control the east bound signals 10, 12 and 14, the line control circuit for the east bound signal 10 is similar to the line control circuit for the west bound signal 13, or in other words, the control circuits for the line relays L^{10} and L^{12} are similar with the exception that they extend in opposite directions. The circuit for the line control relay L^{10} is as follows: wire 120, contact 121 of track relay R^{10} , line wire 122, contact 23 of track relay R^{11} , wire 24, polar contact 25 of east bound polar selector relay S^{12} , wire 100 100, positive polar changer P of signal 12, wires 27 and 28, battery B^{12} , wires 29 and 30, negative pole changer N of signal 12 and the common wire C back to the common terminal of the line control relay L^{10} .

105 The control circuits for the east bound signal 12 is similar to that of the west bound signal 11 with the exception that it extends in the opposite direction and is as follows: from line relay L^{12} , wire 20, contact 21 of track relay R^{12} , line wire 22, contact 23 of track relay R^{14} , line wire 224, contact 225 of track relay R^{15} , wire 226, positive pole changer P of signal 14, wires 227 and 228, battery B^{14} , wire 229, negative pole changer 115 N at the signal 14 and the common wire C back to the line relay L^{12} .

110 The east bound polarized selector relay S^{12} is controlled by a local pole changing circuit which is operated by an east bound line relay L^{12} and is similar to that of the west bound polarized selector relay S^{11} , with the exception that it is controlled by the track relay R^{12} instead of being controlled by the track relay R^{11} , the circuit being as 120 follows: positive side of battery B^{12} , wire 28, wire 31, front contact 32 of line relay L^{12} , wire 33, wire 34, selector relay S^{12} , wire 35, contact 36 of track relay R^{12} , wire 37 to circuit controller 38 of signal 12, wire 130

39, front contact 40 of line relay L^{12} , wire 41, wire 29 to battery B^{12} . The current through this relay S^{12} is also reversed when front contacts 32 and 40 are opened and back 5 contacts 42 and 43 are closed. The line control circuit for line relay L^{14} is similar to the control circuit for line relay L^9 .

The motor circuits for the east bound signals 10, 12 and 14 are in all respects 10 similar to the motor circuits for the west bound signals, the 90° position of the signals being controlled by both the neutral and polar contacts and the 45° position being controlled by the neutral contact alone.

15 It is believed that with this preliminary discussion of the circuits, the invention will now be clear if described in conjunction with the movement of a train over the track sections forming the stretch of track between 20 the sidings W and X , it being understood that this section of track is divided into track sections which have been designated T^9 , T^{10} , T^{11} , T^{12} , T^{14} , T^{15} and T^{16} , each track section being provided with the usual track 25 battery and the track relays R^{10} , R^{11} , R^{12} , R^{14} , R^{15} and R^{16} , respectively. Assume now that an east bound train enters the track sections at the passing siding W , and consider first the action of the presence of this 30 train upon the west bound signals which should be moved to their "stop" positions to give the absolute control. The entry of an east bound train into the track section T^9 will open the circuit of line relay L^9 and 35 the signal 9 will go to danger. The entry of the east bound train into track section T^{10} will cause the contact 165 controlled by the track relay R^{10} to fall and hence open the circuit of the line control relay L^{11} at the 40 signal 11. The deenergization of the line control relay L^{11} will cause the front contacts 32 and 40 to open and the back contacts 42 and 43 to close. These contacts as before described serve as pole changers for 45 the polar selector relay S^{11} and will therefore reverse the current through this relay to cause it to positively open its polar contact 65. The result of opening the circuit at the polar contact 65 is to open the circuit 50 to the line control relay L^{13} which passes through this polar contact. When line control relay L^{13} is deenergized both motor circuits through the signal 13 will be broken and the signal will fall to its "stop" or 55 "danger" position. The signal 11 also will have dropped to its "stop" or "danger" position, since, as before described, the circuit to the line control relay L^{11} has been opened at the contact 165 by the deenergization of 60 the relay R^{10} . When the west bound signal 11 goes to its "stop" position, its circuit controller 38 will be changed to its open position which takes place after the signal has 65 passed below its 45° position and the local pole changing circuit to the selector relay

S^{11} will then be held open at this point. The deenergization of the polar relay S^{11} at this time will have no effect upon the operation of the system, since the permanent magnetic member 65 will remain open, it being 70 understood that once the polar contact 65 is opened by a reverse current passing through the selector relay S^{11} , the contact remains open until current of a normal direction is again passed through the relay. Moreover 75 the interval elapsing from the time of closing the back contacts 42 and 43 of the line control relay L^{11} until the opening of the circuit controller 38, is of sufficient duration, to cause the reversed current passing 80 through the selector relay S^{11} to open its contact 65.

It will therefore be seen that just as soon as an east bound train enters the track section T^{10} , both the west bound signals 11 85 and 13 will move to their "danger" or "stop" positions. These signals remain in their "danger" or "stop" positions while the east bound train is in track sections T^{11} and T^{12} , since the circuit for the line relay 90 L^{11} is controlled by the contacts 61 of R^{12} and the contact 63 of R^{11} in the same manner as it is controlled by the contact 165 of R^{10} , as has been described.

As the train enters the track section T^{12} , 95 the contact 36 of track relay R^{12} will open the circuit of selector relay S^{12} which will prevent this polarized relay from being reversed when the east line control relay L^{12} drops and the signal 12 goes to "stop," it being clear that the circuit for the line control relay L^{12} is controlled by the contact 21 of track relay R^{12} and if the circuit of the polar selector relay S^{12} were not open at the contact 36, the closing of the back contacts 42 and 43 of the line relay L^{12} would cause a reversal of current through the polar selector relay S^{12} . In order to insure that the circuit to the selector relay S^{12} will be open at the contact 36 prior to the closing of 100 the back contacts 42 and 43 of line relay L^{12} , the line relay is preferably a slow releasing relay, it being understood, however, that the line relay L^{12} will release prior to the movement of the circuit controller 38 105 from its 90° position to a position below its 45° position.

When the east bound train leaves the track section T^{12} , track relay R^{12} will close its contact 36, but the circuit controller 38 110 for the signal 12 being open since this signal has dropped to its zero position when the circuit to the line relay L^{12} was broken at the contact 21 of track relay R^{12} , no current will flow from the battery B^{12} through 115 the selector relay S^{12} which will therefore remain deenergized, its polar contact 25 remaining in its normal or closed position.

However, when track relay R^{11} again becomes energized, its contact 23, which is 120

included within the circuit of the line control relay L^{10} , will complete the closing of the circuit through this line control relay, which will close the 45° motor circuit for 5 the signal 10. This is true because a current of reverse polarity is passing through the line control relay L^{10} , due to the fact that the signal 12 is now in its stop position and its pole changers P and N, which are 10 now reversed, are included in the circuit of the line control relay L^{10} . The reverse current through this relay maintains its polar contact which controls the 90° motor position open, and this holds signal 10 at 15 45° . This gives the permissive signal to a following east bound train.

As the train passes through the track sections T^{14} and T^{15} , the selector relay S^{12} will remain deenergized since the control circuit for this relay is controlled by circuit controller 38, now open, of signal 12 whose line relay L^{12} is controlled by the track relays of these respective track sections. However, when the east bound train clears 25 out of track section T^{15} , the closing of the contact 225 of track relay R^{15} will close the control circuit for east bound line control relay L^{12} , which will now become energized and by closing its contact 52 will close the 30 motor circuit for the 45° position of the signal 12, it being understood that the polar contact 56 of the line relay L^{12} is not closed because current of reverse direction passes through the line control relay L^{12} due to 35 the fact that the presence of a train in the track section T^{16} causes the signal 14 to drop to its "stop" position, which will by virtue of its pole changer reverse the direction of current in the line control circuit for 40 the relay L^{12} . However, the movement of the signal 12 to its 45° position will again close the circuit controller 38 at the signal 12 which will restore the normal energized condition of the selector relay S^{12} .

45 It should, therefore, be noted that while an east bound train is in the track sections T^{12} , T^{14} and T^{15} , the selector relay S^{12} is deenergized and cannot be reversed, and its polar contact 25 remains closed.

50 As previously explained, the presence of an east bound train in track section T^{10} causes the west bound selector relay S^{11} of signal 11 to be reversed and its polar contact 65 moved to its open position for holding the west bound absolute signal 13 at stop. This reverse condition of the selector relay S^{11} will continue until the east bound train has cleared out of track section T^{14} . This is true because when the east bound 55 train is in track sections T^{10} , T^{11} and T^{12} , the line control relay L^{11} remains deenergized,—since contact 165 of track relay R^{10} , contact 63 of track relay R^{11} and contact 61 of track relay R^{12} are successively opened. 60 65 When the east bound train clears out of

track section T^{12} , track relay R^{12} by closing its contact 61 will close the control circuit for the west bound control relay L^{11} and this control circuit will then again be energized. The energization of line control relay L^{11} will cause its neutral contact 52 to be closed to clear the signal 11 which is the regular operation since the train has now passed beyond this signal.

The energization of the line control relay L^{11} will also open its back contacts 42 and 43 and close its front contacts 32 and 40, which will partially restore the normal condition of the pole changing circuit for the west bound selector relay S^{11} . However, the deenergized condition of the track relay R^{14} will, by holding its contact 36 open, prevent the west bound selector relay being restored to its normal energized condition until after the train has passed out of track section T^{14} when its polar contact 65 will be closed. The absolute west bound signal 13, however, remains at "danger" until the east bound train passes out of track section T^{15} , since the contact 261 of track relay R^{15} controls this circuit. When the train passes out of track section T^{15} , the closing of this contact will energize the line relay L^{13} and clear the signal 13.

For a west bound train the east bound selector relay S^{12} operates in the manner similar to the one described for an east bound train, and is as follows: While the west bound train is in the track sections T^{15} , T^{14} and T^{12} , the deenergized condition 100 of the east bound line relay L^{12} at the signal 12 will, by its back contacts 42 and 32, cause the current through the selector relay S^{12} to be reversed and its contact 25 will be moved to its open position and held open. The 105 opening of this contact by the deenergization of the line relay L^{12} causes the east bound signal 10 to go to its "stop" position. When the west bound train clears out of track section T^{12} , the east bound line relay L^{12} will be again energized which will restore 110 the east bound selector relay S^{12} to its normal condition.

The embodiment of the invention described is suitable for a short block section 115 between two passing sidings where a pair of intermediate signals, such as 11 and 12, are alone necessary. For longer blocks any number of intermediate signals in either single or double locations may be used, and 120 it is not the intention to limit the invention to the embodiment shown but only by the scope of the claims appended hereto.

I claim:

1. In an electric railway signal system, a 125 stretch of single track divided into track sections, two signals along said track for governing traffic in one direction, means including a line relay for controlling each of said signals, means including a polarized relay 130

for causing the operation of the signals in one order when a train passes along the trackway in the direction governed by said signals and in a different order when the 5 train passes along the trackway in the opposite direction, and means operated by the train upon entering the stretch while traveling in said opposite direction and located at a point in advance of the train for controlling the polarized relay.

2. In an electric railway signal system, a stretch of single track divided into track sections, two signals along said track for governing traffic in one direction, means 15 including a line relay for controlling each of said signals, means including a polarized relay for causing the operation of the signals in one order when a train passes along the trackway in the direction governed by 20 said signals and in a different order when the train passes along the trackway in the opposite direction, and means operated by the train upon entering the stretch while traveling in said opposite direction and located at a point in advance of the train for controlling the polarity of the polarized relay.

3. In an electric railway signal system, a stretch of single track divided into track 30 sections, two successive signals along said track for governing traffic in one direction, the rear signal being at the entrance to the stretch in the governed direction and the advance signal being at an intermediate 35 point in said stretch and being responsive to the condition of the track in advance thereof, a line relay in control of each signal, a polarized relay in control of the line relay for the rear signal, and means for reversing 40 the current through the polarized relay when a train enters the stretch of track in one direction only.

4. A railway signal system comprising a stretch of track, a plurality of signals 45 along said track for governing traffic in one direction, a line relay in control of each signal, one relay being responsive to the condition of the track in advance of its signal, and a polarized selector relay the 50 polarity of which is controlled by the said line relay and which is arranged to control the line relay in the rear.

5. A railway signal system comprising a stretch of track, a plurality of signals along 55 said track for governing traffic in one direction, a line relay in control of each signal, one relay being responsive to the condition of the track in advance of its signal, a polarized selector relay the polarity of 60 which is controlled by the said line relay and which is arranged to control the line relay in the rear, and means controlled by the train for deenergizing the polarized relay before the line relay operates to reverse 65 the polarity of the polarized relay when

the train passes through the stretch of track in the direction governed by said signals.

6. In an electric railway signal system, a stretch of single track divided into track sections, a plurality of signals along the 70 trackway, track relays for said sections, polarized line relays having their circuits controlled by said track relays, line circuits for said line relays, pole changers actuated by said signals and included in said line 75 circuits, a polar relay having its polar contact included in one of said line circuits, and a local circuit for the magnet of said polar relay including pole changes controlled by another of said line relays. 80

7. In an electric railway signal system, a stretch of single track divided into track sections, a plurality of signals along the trackway, track relays for said sections, polarized line relays having their circuits controlled by said track relays, line circuits for 85 said line relays, pole changers actuated by said signals and included in said line circuits, a polar relay having its polar contact included in one of said line circuits, and a local circuit for the magnet of said polar relay including pole changers controlled by another of said line relays, said local circuit being also controlled by the signal controlled by said last named relay. 95

8. In an electric railway signal system, a stretch of single track divided into track sections, a plurality of signals along the trackway, a polarized line relay for each signal having neutral and polar contacts 100 controlling said signal, line circuits for said relays controlled by track relays of said track sections and by pole changers at a signal in advance, whereby a train passing through the stretch of track in a normal 105 direction successively controls said signals, a polarized selector relay for controlling the line circuit at the beginning of the stretch of track, and means controlled by a train entering the track section at the end of the 110 stretch of track and in the opposite direction for controlling the polarity of said selector relay.

9. A railway signal system comprising a stretch of track divided into blocks, a plurality of signals along said track for governing traffic in one direction, a track relay for each block responsive to the condition of the block, a line relay in control of each signal, one relay being responsive to the condition of the track in advance of its signal, a polarized selector relay arranged 115 in control of the line relay in the rear, and a local circuit for the selector relay including a pole changer controlled by the 120 first line relay, the local circuit being also controlled by an adjacent track relay. 125

10. A railway signal system comprising a stretch of track divided into blocks, a plurality of signals along said track for gov- 130

erning traffic in one direction, a track relay for each block responsive to the condition of the block, a line relay in control of each signal, one relay being responsive to the condition of the track in advance of its signal, a polarized selector relay arranged in control of the line relay in the rear, and a local circuit for the selector relay including a pole changer controlled by the first line relay, the local circuit being also controlled by an adjacent track relay, the first line relay being slow acting relative to said track relay.

11. A railway signal system comprising a stretch of track divided into sections, a plurality of signals along said track for governing traffic in one direction, one signal for each section, a relay in control of the first signal, a normally closed line circuit for the said relay, a polarized relay in control of said line circuit and operative to open the circuit when its normal polarity is reversed,

and means for reversing the polarity of the polarized relay operated by the entrance of a train into the stretch of track in a direction opposite that governed by said signals. 25

12. In an electric railway signal system, a stretch of single track divided into track sections, a plurality of signals along the trackway, a polarized line relay for controlling each signal, line circuits for said relays controlled by track relays and pole changers at the signals, and means for effecting an additional control of one of said line circuits comprising a polarized relay 35 and a circuit for said relay at an intermediate signal, said circuit having a pole changer therein controlled by the line relay of said last named signal, and said circuit also having a circuit controller there- 40 in controlled by said last named signal.

In witness whereof I subscribe my signature.

ROBERT J. HEWETT.
